United States Patent Office

Des. 222,526
Patented Nov. 2, 1971

222,526

SNUBBER PLATE

William A. Meier, Roselle, Ill., assignor to Signode Corporation

Filed Mar. 27, 1970, Ser. No. 22,079

Term of patent 14 years

Int. Cl. D8—03

U.S. Cl. D8—229

FIG. 1 is a top perspective view of a snubber plate showing my new design;

FIG. 2 is a top plan view thereof;

FIG. 3 is a front elevation thereof;

FIG. 4 is a bottom plan view thereof; and

FIG. 5 is a side elevation thereof.

I claim:

The ornamental design for a snubber plate, substantially as shown.
